UNITED STATES PATENT OFFICE.

OVERTON WINSTON, OF MINNEAPOLIS, MINNESOTA.

BULB-STENCILING DEVICE.

1,258,290.

Specification of Letters Patent. Patented Mar. 5, 1918.

Application filed December 1, 1916. Serial No. 134,283.

To all whom it may concern:

Be it known that I, OVERTON WINSTON, a citizen of the United States, residing at Minneapolis, in the county of Hennepin and 5 State of Minnesota, have invented certain new and useful Improvements in Bulb-Stenciling Devices; and I do hereby declare the following to be a full, clear, and exact description of the invention, such as will enable others skilled in the art to which it 10 pertains to make and use the same.

My invention has for its object to provide an extremely simple and highly efficient stenciling device for use in accurately, 15 quickly and economically applying to electric light bulbs, or the like, frosting or light dimming surfaces. The stenciling device of the present application is in the nature of a modification of or improvement on the 20 stenciling device disclosed and broadly claimed in my companion application S. N. 133,473, filed of date November 25th, 1916, and entitled "Bulb stenciling device."

Generally stated, the invention consists of 25 the novel devices and combinations of devices hereinafter described and defined in the claims.

It has been found desirable to provide 30 frosted or dimmed surfaces or zones of various different shapes at proper precalculated places on the globes of electric light bulbs which are to be used in headlights on automobiles and similar vehicles, and my invention provides an extremely simple and efficient 35 device for this purpose.

In the accompanying drawings which illustrate the invention, like characters indicate like parts throughout the several views.

Referring to the drawings:

40 Figure 1 is a bottom plan view of the improved stenciling device;

Fig. 2 is a vertical section on the line 2-2 of Fig. 1;

Fig. 3 is a transverse section on the line 45 3-3 of Fig. 1;

Fig. 4 is a fragmentary section on the line 4-4 of Fig. 2; and

Fig. 5 is a fragmentary view partly in side elevation and partly in vertical section showing a portion of the bulb and a portion of 50 the socket member of the stenciling device.

The body or socket member of the stenciling device which is indicated, as an entirety, by the numeral 6, is intended to be 55 rigidly secured to a suitable support, not shown, and it is formed with a vertical pas-

sage 7, which, at 8, joins a concave bulb seat 9 that flares toward and opens at the bottom of the said socket member. In spherical light bulbs, the passage 7 should 60 be approximately cylindrical and the bearing shoulder 8 should also be a true circle except at its extreme front, where it is slightly indented, so that the light bulb, when seated against the same, will have continuous contact therewith, but will not have contact with the flaring walls of the pocket 9.

The stencil plate 10, in this form of the device, is a rigid structure, being preferably a casting, and it is of an approximately 70 spherical form having, at one side, an upwardly extended hood 11, and having at its other side, a hinge lug 12, which latter is loosely connected by a hinge pin 13, to laterally spaced lugs 14 on the bottom of the 75 socket member 6.

In this lower or bottom portion, the stencil plate 10 is formed with stencil openings 15 and 16, the margins of which are formed by sharp edges which, alone, engage the 80 bottom of the electric light bulb. The globe of this electric light bulb is indicated by the numeral 17, and its shank by the numeral 18, the latter having the customary diametrically projecting lock lugs 19. The 85 main inner surface of the stencil plate 10, as is clearly shown in Fig. 2, stands considerably away from the surface of the light bulb. Alined with the tip 17^a of the light bulb globe, the stencil plate 10 is formed 90 with a depressed pocket 20 that is formed with a rim projected within the concave inner surface of the stencil plate but not into contact with the bulb globe. In front of the stencil opening 16, the stencil plate 10 is 95 provided with a segmental trough or depression 21 which has perforations or drain passages 22 and 23, all for a purpose which will presently appear.

The trough or depression between the two 100 stencil openings 15 and 16 is provided with a drain passage 24, and the depression or trough between the stencil opening 15 and rim of the pocket 17^a, has a drain passage 26. The purpose of these drain passages will 105 presently appear.

At the intermediate portions of its sides, the stencil plate 10 is provided with outstanding lugs 27 that are attached to the lower ends of coiled springs 28, the upper 110 ends of which are anchored to ears 29 on the sides of the socket member 6.

By reference to Fig. 2, it will be noted that the under surface of the socket member 6 is oblique, so that the pocket 9 nearly or quite disappears at the front of the device and it 5 will be further observed that, at its lower front portion, said socket member is formed with a concave seat 30 that fits the shank 18 of the light bulb. When the bulb is in position, as shown in Fig. 2, its shank will be 10 held against the said seat 30 by means of a light leaf spring 31 which is attached at one end of the hood 11 and has a transversely concave end that directly engages the shank of the bulb. The free end of this spring 31 15 terminates inward of the lugs 19 of the bulb shank so that the bulb may be freely rotated while it is held, as shown in Fig. 2. The sides of the hood are cut away so that the bulb shank may be engaged by the fingers 20 while held, as shown in Fig. 2. It will be further noted that the springs 28 exert a force that is at a right angle to the plane of the socket ledge 8, and it will be further observed by reference particularly to Fig. 1, 25 that the hinge lug 12 has play on the hinge pin 13 and between the lugs 14 so that the stencil plate is free for limited lateral and forward and rearward movements to adapt itself to the surface of the light bulb, when 30 the latter is spring-pressed against the ledge 8.

In its front portion, the socket member 6 is provided with a peek hole 32 that extends radially toward the axis of the bulb, and 35 which enables an observer looking through the same, to note the exact position of the filament of the light bulb, and hence will rotate the bulb until its filament is properly positioned in respect to the stencil openings 40 15 and 16. This is especially important when the frostings are to be applied to an electric light bulb having two filaments, or even one filament that is extended transversely of the axis of the bulb. 45 When the bulb is applied and held in the stenciling device, as shown in Fig. 2, those portions thereof that may be seen through the stencil openings 15 and 16, are exposed so that by means of a brush, or otherwise, 50 an acid or other material which will produce a frosting or light dimming effect on the glass or the bulb, may be applied through the said stencil openings, and thus produce frostings or light dimming surfaces having the form of said stencil openings. 55 This device is also well adapted to hold a bulb while a frosting or ground glass effect is produced by means of a sand blast blown through the said stencil openings. 60 When the acid is applied, as above described, some thereof may lead past the sharp marginal edges of the stencil openings and into the cavities of the concave stencil plate 10, but any liquid thus leaking may 65 run out again immediately through the

drain passages 22, 24 and 26. When the stencil plate is lowered by application of a finger to the finger piece 33, any further acid or liquid remaining in the cavity of the stencil plane finds its ready escape 70 through the drain passage 23.

The pocket 20 serves roughly as a means for primarily positioning the bulb within the concave stencil plate 10. After the bulb has been frosted and the stencil plate 10 75 is removed downward to release the bulb, the spring 31 tends to rock the bulb and would tend to produce a scraping action between the bulb and the sharp marginal edges of the stencil openings 15 and 16. 80 This, however, is prevented by a light folded leaf spring 34 (see particularly Figs. 2 and 3). This spring is preferably bent upon itself, has one end rigidly anchored to the bottom of the stencil plate between the 85 openings 15 and 16, and has a curved free end portion that engages the bottom of the bulb, and not only tends to keep the bulb centered laterally, but serves to raise the bulb out of engagement with the sharp edges 90 of the stencil openings 15 and 16, the instant that pressure is removed therefrom by the downward movement of the stencil plate.

What I claim is:

1. A bulb stenciling device comprising a 95 socket member and a coöperating stencil plate pivoted thereto, the latter being a rigid structure having a stencil opening with inturned edges for engagement with the globe of a light bulb held between said socket member and stencil plate, and the said stencil plate having a pocket adapted to loosely receive a portion of the bulb.

2. A bulb stenciling device comprising a 100 socket member and a coöperating stencil plate pivoted thereto, the latter being a rigid structure having a stencil opening with inturned edges for engagement with the globe of a light bulb held between said socket member and stencil plate, said stencil 105 plate having a projecting shank receiving hood and a spring in said hood engageable with the shank of the light bulb to press the same against a lower edge portion of said socket member.

3. A bulb stenciling device comprising a 110 socket member and a coöperating stencil plate pivoted thereto, the latter being a rigid structure having a stencil opening with in-turned edges for engagement with the globe 115 of a light bulb held between said socket member and stencil plate, said stencil plate having a projecting shank receiving hood and a spring in said hood engageable with the shank of the light bulb to press the same against a lower edge portion of said socket member, the said socket member having a concave seat receiving the shank thus 120 pressed against the same.

4. A bulb stenciling device comprising a 125

- socket member and a coöperating stencil plate pivoted thereto, the latter being a rigid structure having a stencil opening with in-turned edges for engagement with the globe of a light bulb held between said socket member and stencil plate, said stencil plate having a projecting shank receiving hood and a spring in said hood engageable with the shank of the light bulb to press the same against a lower edge portion of said socket member, the said socket member having a concave seat receiving the shank thus pressed against the same, and the said stencil plate, at a point opposite to said hood having a pocket that loosely receives the tip of the bulb. 5
5. A bulb stenciling device comprising a socket member and a coöperating stencil plate pivoted thereto, the latter being a rigid structure having a stencil opening with in-turned edges for engagement with the globe of a light bulb held between said socket member and stencil plate, the said stencil plate having a depression adjacent 10 to its stencil opening provided with drain passages for the purposes set forth. 20
6. A bulb stenciling device comprising a socket member and a coöperating stencil plate pivoted thereto, the latter being a rigid structure having a stencil opening with in-turned edges for engagement with the globe of a light bulb held between said socket member and stencil plate, the said stencil plate, at its lower portion, adjacent to its 25
- stencil opening, having a spring tending to raise the bulb from its seat. 30
7. A bulb stenciling device comprising a socket member and a coöperating stencil plate pivoted thereto, the latter being a rigid structure having a stencil opening with in-turned edges for engagement with the globe of a light bulb held between said socket member and stencil plate, the said stencil plate, at its lower portion, adjacent to its stencil opening, having a spring tending to raise the bulb from its seat, and the said stencil plate having further a spring engageable with the shank of the bulb to press the same against the lower edge portion of said socket member. 35
8. In a bulb stenciling device, the combination with a socket member, of a concave stenciling plate hinged thereto at one side and spring-connected thereto at its intermediate portion, said stencil plate, at its bottom having a plurality of stencil openings with in-turned edges for engagement with the bulb and having outward of said stencil openings, a depressed trough with drain passages for the purposes set forth. 40
- In testimony whereof I affix my signature in presence of two witnesses. 45
